UNITED STATES PATENT OFFICE

128,172

DESIGN FOR A READING STAND

Jay Alva Morgan, Chicago, Ill.

Application April 2, 1941, Serial No. 100,098

Term of patent 7 years

To all whom it may concern:

Be it known that I, Jay Alva Morgan, a citizen of the United States, residing at Chicago, in the county of Cook and State of Illinois, have invented a new, original, and ornamental Design for a Reading Stand, of which the following is a specification, reference being had to the accompanying drawing, forming a part thereof.

In the drawing:

Figure 1 is a front elevational view of a reading stand, showing my new design.

Figure 2 is a side elevational view of the reading stand in the position of use.

Figure 3 is a rear elevational view of the reading stand with the support element in folded position.

Figure 4 is a perspective view of the reading stand with the support element in the same position as in Figure 2.

I claim:

The ornamental design for a reading stand, substantially as shown.

JAY ALVA MORGAN.
